Patented Oct. 17, 1916.

UNITED STATES PATENT OFFICE.

WALTER P. MURPHY, OF CHICAGO, ILLINOIS

PRESSED-STEEL CAR END.

1,201,857.

Specification of Letters Patent. Patented Oct. 17, 1916.

Application filed February 19, 1915. Serial No. 9,331.

To all whom it may concern:

Be it known that I, WALTER P. MURPHY, a citizen of the United States, residing at Chicago, in the county of Cook and State 5 of Illinois, have invented certain new and useful Improvements in Pressed-Steel Car Ends, of which the following is a specification.

My invention relates to an end structure 10 for railway cars, particularly box cars, and more especially to an end made up of plates or panels of sheet metal pressed or otherwise formed with strengthening and rigidifying corrugations; and the principal object 15 of the invention is to provide a structure of this character comprising a plurality of superposed plates or panels formed with corrugations which extend at an angle to each other, one set preferably extending horizontally across the end of the car from one corner post to the other, and the other corrugations extending vertically from the end plate to the sill; said corrugations constituting structurally, crossed beams or arches 20 giving the end strength and rigidity to withstand external shocks, but more particularly the stresses, shocks and pressures from the inside of the car due to shifting cargoes.

The invention has for further objects such 25 other new and improved constructions, arrangements and devices relating to sheet metal car ends as will be hereinafter described and claimed.

The invention is illustrated, in a preferred 30 embodiment, in the accompanying drawing wherein—

Figure 1 is an end elevation of the superstructure of a railway box car provided with a sheet metal corrugated reinforced end constructed in accordance with my invention, 35 and Fig. 2 is a vertical sectional view taken on line 2—2 of Fig. 1.

Referring to the drawing, the end sill of 40 the car is designated 10, the end plate 11, the roof 12, the flooring 13, and the corner posts 14.

The end structure, in the preferred embodiment shown, consists of three sheet metal plates or panels 15, 16, 17 formed with 45 horizontal corrugations 18, 18^a, and two plates or reinforcing members 19, 19, formed with corrugations 20 which extend vertically, the panels 19 being superposed upon the panels 15, 16, 17 and secured thereto at 50 intervals by rivets 21. The panels 15, 16, 17 have their edges overlapped and riveted to-

gether by rivets 22. The upper panel 15 is secured to the end plate 11 by bolts 23. The lower panel 17 is preferably formed with an inturned flange 24 which intervenes 55 between the flooring of the car and the end sill 10 and is suitably anchored to the latter. All three panels 15, 16, 17 are formed with angular flanges 25 which overlap and are secured to the corner posts 14. The panels 60 19 are fastened to the end plate 11 by bolts 26. The attachment of the end structure to the framing of the car is preferably made more secure by means of gussets 27 and tie bolts 28.

The corrugations 18, 18^a, project alternately outwardly and inwardly and terminate within the edges of the panels, the corrugations preferably merging one directly into the other so that the center portion of the structure consists of a series of horizontal beams or arches one directly above the other. The corrugations taper or merge into the flat marginal portions.

The corrugations 20 are preferably deepest and widest at points below the center horizontal line of the end structure and taper gradually toward their extremities. Thus beams or arches are provided which cross the beams constituted by corrugations 65 18, 18^a, the thickest or deepest portions of which are in the lower portion of the end where the cargo thrusts are likely to be heaviest.

The upper panel 15 is preferably formed 70 with a door opening 29 closed by a sheet metal door 30 held in place by a locking bar 31. The door construction, however, is not claimed herein.

While I have described my invention in a 75 preferred embodiment, it will be understood that modifications might be made without departure from the principles of the invention. The number of panels might obviously be varied for example. Therefore I 100 do not wish to be understood as limiting the invention to the precise constructions, arrangements and devices shown except so far as the claims are expressly so limited.

I claim:

1. An end structure for a railway car 105 comprising a plurality of superposed plates formed with strengthening corrugations which terminate within the edges of said plates so as to leave flat marginal attaching portions, one set horizontally and the other vertically, the vertically extending

- corrugations having greatest cross sectional area below their middle points and being tapered toward their extremities.
2. An end structure for a railway car comprising a plurality of superposed plates formed with strengthening corrugations, one set horizontally and the other vertically, the vertical corrugations having the greatest cross sectional area at points intermediate their extremities and tapering gradually toward said extremities.
3. An end structure for a railway car comprising a plurality of superposed plates formed with strengthening corrugations, one set horizontally and the other vertically, the vertical corrugations having the greatest cross sectional area at points below the horizontal center line of the end and being tapered gradually toward their extremities.
4. An end structure for a railway car comprising a plurality of superposed plates formed with strengthening corrugations, one set horizontally and the other vertically, the horizontal corrugations being of substantially uniform cross sectional area for most of their length, the vertical corrugations being deepest and widest at points below the center horizontal line of the end and tapering gradually toward their extremities.
5. An end structure for a railway car comprising a plurality of superposed plates formed with strengthening corrugations, one set horizontally and the other vertically, one set of corrugations being of substantially uniform cross sectional area for most of their length, the corrugations running in the other direction having a maximum cross sectional area at points intermediate their extremities and tapering gradually toward said extremities.
6. An end structure for a railway car comprising a plurality of panels with their edges overlapped and joined together and formed with parallel corrugations which project alternately inwardly and outwardly, one merging directly into the other, and a plurality of reinforcing elements secured to the face of said panels and extending across and at right angles to said corrugations.
7. An end structure for a railway car comprising a plurality of panels with their edges overlapped and joined together and formed with horizontal corrugations which project alternately inwardly and outwardly, one merging directly into the other, and a plurality of reinforcing elements secured to the face of said panels and extending across and at right angles to said corrugations.
8. An end structure for a railway car comprising a plurality of panels with their edges overlapped and joined together and formed with parallel corrugations which project alternately inwardly and outwardly, one merging directly into the other, and a plurality of reinforcing elements secured to the face of said panels provided with reinforcing corrugations which extend across and at right angles to the aforesaid corrugations.
9. An end structure for a railway car comprising a plurality of panels with their edges overlapped and joined together and formed with horizontal corrugations which project alternately inwardly and outwardly, one merging directly into the other, and a plurality of reinforcing elements secured to the face of said panels formed with vertically extending corrugations which extend across the aforesaid corrugations.
10. An end structure for a railway car comprising a plurality of panels with their edges overlapped and joined together and formed with corrugations which project alternately inwardly and outwardly, one merging directly into the other, and a plurality of reinforcing elements secured to the face of said panels and extending across and at right angles to said corrugations.
11. An end structure for a railway car comprising a plurality of panels with their edges overlapped and joined together and formed with horizontal corrugations which project alternately inwardly and outwardly, one merging directly into the other, and reinforcing elements secured to the face of said panels formed with vertically extending corrugations which extend across the aforesaid corrugations, the vertical corrugations having the greatest cross sectional area at points below the horizontal center line of the end and tapering toward their extremities.
12. An end structure for a railway car comprising a plurality of panels with their edges overlapped and joined together and formed with parallel corrugations of substantially the same cross sectional area throughout the greater part of their length, which corrugations project alternately inwardly and outwardly, one merging directly into the other, and reinforcing members provided with corrugations across the aforesaid corrugations which have the greatest cross sectional area at points intermediate their extremities and taper gradually toward said extremities.
13. An end structure for a railway car comprising a sheet metal element, the middle portion of which is formed with parallel corrugations, the marginal portions being flat so as to provide attaching flanges, and members provided with corrugations which extend at an angle across the aforesaid corrugations.
14. An end structure for a railway car comprising a sheet metal element, the middle portion of which is formed with parallel corrugations, the marginal portions being flat so as to provide attaching flanges, and members provided with corrugations which ex-

tend at right angles across the aforesaid corrugations.

15. An end structure for a railway car comprising a sheet metal element, the middle portion of which is formed with parallel corrugations, the marginal portions being flat so as to provide attaching flanges, and members provided with corrugations which extend at right angles across the aforesaid corrugations which have their greatest cross sectional area at points intermediate their extremities and taper gradually toward said extremities.

16. In a railway box car, the combination with the framing and end wall of the car, of means for reinforcing said end wall comprising a pair of pressed steel members attached at their extremities to the upper and lower members of the end framing, and formed each with a stiffening corrugation terminating within the extremities of said members.

17. In a railway box car, the combination with the framing and end wall of the car, of means for reinforcing said end wall comprising a pair of pressed steel members attached at their extremities to the upper and lower members of the end framing, and formed each with a stiffening corrugation terminating within the extremities of said members, which corrugations have a maximum cross sectional area at places between their extremi-

ties and taper from said places of maximum cross sectional area gradually toward their extremities.

18. In a railway box car, the combination with the framing and end wall of the car, of means for reinforcing said end wall comprising a pair of pressed steel members attached at their extremities to the upper and lower members of the end framing, and formed each with a stiffening corrugation terminating within the extremities of said members, which corrugations have a maximum cross sectional area at points below the horizontal center line of the end wall, and taper from said places of maximum cross sectional area gradually toward their extremities.

19. In a railway box car, the combination with the end framing of the car, of a sheet metal end structure attached to said end framing and formed with a plurality of substantially vertical corrugations having their maximum cross sectional area below the horizontal center line of the end, and tapering from said places of maximum cross sectional area gradually toward their extremities and terminating within the edges of said sheet metal end structure.
